UNITED STATES PATENT OFFICE.

DANIEL W. SHIEK, OF CHICAGO, ILLINOIS, ASSIGNOR, BY MESNE ASSIGNMENTS, TO
WALTER L. MILLIKEN, TRUSTEE.

RIBBON-FEED MECHANISM FOR COMPUTING-MACHINES AND THE LIKE.

963,819.

Specification of Letters Patent. Patented July 12, 1910.

Application filed December 30, 1903. Serial No. 187,125.

To all whom it may concern:

Be it known that I, DANIEL W. SHIEK, a citizen of the United States, residing at Chicago, in the county of Cook and State of Illinois, have invented certain new and useful Improvements in Ribbon-Feed Mechanism for Computing-Machines and the Like, of which the following is a description.

10 The purpose of this ribbon-feed mechanism is to feed or move an inked ribbon which is used for printing purposes, such as in typewriting machines, and computing machines; my invention being especially adapted to the last-named class of machines.

15 To this end my invention consists in the novel construction, combination and arrangement of parts, as herein described, and pointed out in the claims.

20 In the accompanying drawings: Figure 1 is an elevation of a preferred ribbon-feed mechanism embodying my invention, the ends of the actuating-shaft being broken off; Fig. 2 is a sectional side elevation of 25 one of the spools and its actuating means taken on line *a*—*b*; Fig. 3 is a central section of one of the spools, its shaft, and friction devices; Fig. 4 is a top view of one of the spools, showing its openings; Figs. 5, 6 30 and 7 illustrate modified shapes of ratchet teeth and their pawls; Fig. 8 is an elevational view of my automatic ribbon-reversing device, attached to the feeding and reversing mechanism shown in Fig. 1; Fig. 9 is a detached view of one of the reversing levers; 35 Fig. 10 is a top view of the spring 39.

1 is a plate, above which are mounted the ribbon-spools 3 and 3. As shown sectionally in Fig. 3, each spool is pinned, or otherwise secured, on a shaft or spindle 4. Fixed upon the respective shafts 4 and 4 are two ratchet-wheels 5 and 5, which are preferably of the type known as "crown" ratchet-wheels, having their teeth upon their lower 45 sides, as shown in the drawings.

6 is a longitudinally-movable rock-shaft, on which are secured two pawl-supporting or carrying arms 7 and 7. Mounted pivotally on said respective arms are two pawls 50 8 and 8, which are adapted to engage the respective ratchet-wheels 5, but not both at the same time. The pawls are so positioned and spaced that when either pawl is in engagement with its ratchet-wheel, the other pawl 55 is disengaged from the other ratchet-wheel.

Formed in each ratchet-wheel within the teeth thereof is a circular recess, as 9 in Fig. 3, and the point of the pawl 8 may play idly within said recess when the pawl is disengaged from the ratchet teeth by shifting 60 of the rock-shaft 6. The pawl-carrying arms 7 are oscillated by any suitable means, preferably by a rotatable shaft 10 having a cut-away portion 14, and by a spring 12 or its equivalent. The shaft is cut away as 65 shown at 14, at a point adjacent to one of the pawl-arms 7, and said pawl-arm is held against the shaft by the spring 12 which is preferably coiled around the rock-shaft 6, and has one end connected to one of the 70 pawl-arms while at the other end it bears against the other shaft 10. Thus, the pawl-arms 7 are positively moved to turn the ratchet-wheels 5, by rotation of shaft 10, while the reverse or backward strokes of the 75 pawls are actuated by the spring 12; it being understood, as above explained, that only one spool is positively rotated, the other being rotated through the intermediary of the ribbon. Cams might be mounted on 80 shaft 10 in lieu of the cut-away portions 14, but such devices would be obviously inferior equivalents, owing to their greater cost. Knobs, as at 15, may be mounted on the ends of the pawl-carrying shaft 6, and said shaft 85 may have two notches as 16 cut therein, said notches being engaged by a wire spring, as 17, for holding said shaft in either of its two positions. The pawl-actuating shaft 10 may be rotated either continuously or intermittently, by any suitable means actuated by the operation of the printing mechanism (not shown).

18 indicates an inked ribbon, which is wound on the spools in the usual manner, 95 extending from one to the other. The amount of ribbon on either spool at any time may be observed through openings 19 cut in the upper heads of the spools. The direction in which the ribbon will be fed 100 will depend upon the longitudinal position of rock-shaft 6, as will be readily understood. The spools should be provided with frictional devices of some kind, in order to hold the ribbon taut between them. A preferred frictional device for that purpose is illustrated in Fig. 3, in which the hub of the ratchet-wheel is shown provided with two open slots 20 into which extend the ends of a pin 21 which is driven through a transverse 105 110

hole in the shaft 4. By this device, vertical movement of the ratchet-wheel is permitted, independently of said shaft. A sleeve 22, on the shaft is interposed between the ratchet-wheel and the (stationary) plate 1. The ratchet-wheel is held up against said sleeve by a screw 23, and by a bushing 24, made of rubber or similar elastic or compressible material. A washer 25, may be interposed between said bushing and the head of the screw 23. It is evident that the frictional resistance to the rotation of the spool will depend upon the pressure of the screw-head or washer upon the bushing 24. As the inner face or end of the bushing is worn away, the pressure thereon may be maintained by adjusting the screw 23. The sleeve 22 is firmly secured to the plate 1, either by means of a flange 26 or in any preferred manner.

Reference is now had to Figs. 5, 6 and 7, which illustrate modified forms of teeth adapted for the ratchet wheels 5. The purpose of these modifications is to form the ratchet teeth and their pawls in such a way as to facilitate the engagement and disengagement of the latter with the former when the shaft 6 is shifted to reverse the ribbon. In Fig. 5 the teeth, 28, are inclined downwardly, and the end or point of the pawl, 29 is inclined at a similar angle to that of the teeth. In Fig. 6 the backs of the teeth, 30, are level, the same as in Fig. 1, but their edges are inclined, as shown, and the pawl, 29, is cut off at a similar angle to that of the teeth. Fig. 7 represents an arrangement in which the pawl 31, when disengaged from the ratchet teeth, 32, is outside the periphery of the wheel instead of within it. The teeth are inclined upwardly, and the end or point of the pawl is cut at substantially the angle of the teeth. The position and the general shape of the pawls shown in these views are supposed to be similar to those of the pawl 8 shown in Fig. 2.

By the addition of a very few parts to the mechanism shown in Fig. 1, a simple and effective means may be provided for automatically reversing the travel of the ribbon 18 whenever it becomes almost entirely unwound from either of the spools. Such an attachment is shown in its most preferred form in Fig. 8, to which, reference is had. The construction of the ratchet wheels, their pawls, and the shaft actuating the latter, is not necessarily, altered. The rock-shaft 6 is provided at suitable points with two pins or equivalent projections 34 and 34. Arranged between this shaft and the ribbon 18 are duplicate levers 35 and 35. Preferably, the upper end of each lever 35 is forked, to loosely straddle the ribbon, and the lower end of each is forked, to straddle the shaft 6 (see Fig. 9). These levers and the pins 34 are so positioned that normally one or the other of the pins is always in contact with

its respective lever 35. As shown, shaft 6 is at the left, and the right-hand pin 34 is engaged by its lever. The levers are fulcrumed at any suitable points between their ends, preferably nearer the ends that engage the ribbon, as shown at 36 and 36. Fixed upon the ribbon at proper distances from the ends thereof are two buttons or stops, one of which is shown, marked 37, just in the act of engaging its lever 35. The ribbon has been moving in the direction of the arrow, and has become unwound from the right-hand spool. The continued motion of the ribbon will force the button against the lever 35, turning the latter, which by engaging its pin 34 will move shaft 6 to the right, sufficiently far to disengage the acting pawl 8 from its ratchet wheel, but not far enough to engage the other pawl with the other ratchet wheel. Any suitable auxiliary means may be employed for completing the throw of the shaft to bring the opposite pawl into position for actuating the ribbon. The device shown in the drawing consists of a lug 36' and a coöperating spring 39. The lug may be secured to the shaft in any suitable manner; as shown, it is riveted or pinned in a slot cut in the shaft. This lug is formed with two inclined faces 38 which meet at substantially a point, as shown. The end of the spring 39 which engages this lug is shaped substantially as shown, preferably with two inclined sides, which are adapted to slide over the respective inclined faces of the lug as the latter is shifted by movement of the shaft longitudinally. The downward pressure exerted by the spring upon the lug has the effect of completing the longitudinal throw of the shaft after the shaft has been thrown part way by one of the levers 35. The length of the lug is so adjusted that its highest point will be carried past the middle of the spring, before either pawl is released from its ratchet. The spring then effects a reversal of the ribbon, in the manner aforesaid.

I have thus described the preferred forms of my improvements, but it is obvious that various immaterial modifications may be made without departing from the spirit of my invention; hence I do not wish to limit myself to the exact form and construction shown.

By the word "button" in the claims, I mean to include any equivalent of the button, 37.

Having thus described my invention, what I claim as new and desire to secure by Letters Patent is:

1. In ribbon-feed mechanism, a ribbon-holder, and a frictional device comprising a fixed sleeve through which passes the shaft of the holder, a ratchet-wheel on the shaft, and means for maintaining an adjustable degree of pressure between the sleeve and

the ratchet-wheel and also between the sleeve and the holder; substantially as described.

2. In ribbon-feed mechanism, the combination, with a ribbon spool, of a rotary driven member connected to the spool, and an oscillatory driving member adapted to engage the rotary member, one edge of each of the engaging faces of said members being inclined to facilitate the ready engagement 10 of the parts; substantially as described.

3. In ribbon feed mechanism the combination with a ribbon holder, of a rotary ratchet member connected to the holder, and an oscillating driving pawl adapted to engage the ratchet member, one edge of each of the engaging faces of said parts being inclined to facilitate the ready engagement of the parts, substantially as described.

4. In a device of the kind described, ribbon spools provided with oppositely arranged ratchet wheels, a ribbon mounted on said spools and provided with a stop near each end thereof, a longitudinally movable bar having mounted thereon two oscillating 25 pawl arms each provided with a coöperating pawl for one of said ratchet wheels, the two being so spaced that only one pawl is engaged at a time, and means for oscillating said arms, in combination with tripping levers 35 each having one end extended and adapted to contact directly with and shift said shaft and the other end extended in the path of the ribbon and coöperating with said stop, whereby as the ribbon is exhausted upon a spool it automatically and positively shifts the longitudinally movable bar and reverses the rotation of the spools.

5. In a device of the kind described, ribbon feeding mechanism comprising a ratchet 40 wheel provided with a smooth face adjacent its toothed face, a pawl adapted to engage said toothed face to control the movements of said wheel, and said smooth face to release the same, and means for positioning 45 said pawl to engage either of said faces desired.

6. In a device of the kind described, ribbon feeding mechanism comprising a pair of ratchet wheels each provided with a smooth 50 face adjacent its toothed face, a pawl for each ratchet wheel adapted to engage the toothed face to control the movements of its wheel and the smooth face to release the same, and means connecting said pawls for positioning the same to engage either of said 55 faces upon the respective ratchet wheels, said pawl connecting means being adapted to prevent the simultaneous engagement of both pawls with the toothed faces of the 60 wheels.

7. In a device of the kind described, ribbon feeding mechanism comprising a pair of ratchet wheels each provided with a smooth 65 face adjacent its toothed face, a pawl for each ratchet wheel adapted to engage the

toothed face to control the movements of its wheel and the smooth face to release the same and means connecting said pawls for positioning the same to engage either of the faces upon the respective ratchet wheels, 70 said pawl connecting means being adapted to prevent the simultaneous engagement of both pawls with the toothed faces of the wheels, and means for operating said pawls to rotate said wheels.

8. In a device of the kind described, ribbon carrier mechanism comprising a ribbon spool, a collar, and a ratchet wheel, the three being resiliently held together in suitable relative positions upon a shaft and means 80 for regulating the resiliency of such engagement.

9. In a device of the kind described, ribbon feeding mechanism comprising a ratchet wheel provided with a smooth face adjacent 85 its toothed face, a single pawl adapted to engage either of said faces desired and resilient means for maintaining said pawl in position to engage either of said faces, and to prevent its simultaneous engagement 90 with both faces.

10. In a device of the kind described, ribbon carrier mechanism comprising a collar rigidly held in position and a shaft rotatably supported by said collar, in combination with a ribbon spool and a ratchet wheel mounted upon said shaft said spool and ratchet wheel being spaced from one another by the collar and adapted to frictionally engage said collar between them.

11. In a device of the kind described, ribbon carrier mechanism comprising a collar rigidly held in position, and a shaft rotatably supported by said collar, in combination with a ribbon spool and a ratchet wheel 105 mounted upon said shaft said spool and ratchet wheel being spaced from one another by said collar and adapted to frictionally engage said collar between them, and means for preventing rotation between said spool 110 and ratchet wheel.

12. In a device of the kind described, ribbon carrier mechanism comprising a collar rigidly held in position, and a shaft rotatably supported by said collar, in combination with a ribbon spool and a ratchet wheel mounted upon said shaft said spool and ratchet wheel being spaced from one another by said collar and adapted to resiliently engage said collar between them.

13. In a device of the kind described, ribbon carrier mechanism comprising a collar rigidly held in position, and a shaft rotatably supported by said collar, in combination with a ribbon spool and a ratchet wheel 115 mounted upon said shaft and adapted to frictionally engage said collar between them, and means for forcing said spool and ratchet wheel toward each other.

14. In a device of the kind described, rib-

bon carrier mechanism comprising a collar rigidly held in position, and a shaft rotatably supported by said collar, in combination with a ribbon spool and a ratchet wheel 5 mounted upon said shaft said spool and ratchet wheel being spaced from one another by said collar and adapted to frictionally engage said collar between them, and means for adjusting the frictional 10 engagement between said spool and ratchet wheel and said collar.

15. In a device of the kind described, ribbon carrier mechanism comprising a collar rigidly held in position, and a shaft rotatably supported by said collar, in combination with a ribbon spool and a ratchet wheel mounted upon said shaft and adapted to frictionally engage said collar between them, means for preventing rotation between said 20 spool and ratchet wheel, and means for resiliently forcing said spool and wheel toward each other.

25. In a device of the kind described, ribbon carrier mechanism comprising a collar rigidly held in position, and a shaft rotatably supported by said collar, in combina-

tion with a ribbon spool and a ratchet wheel mounted upon said shaft and adapted to frictionally engage said collar between them, means for preventing rotation between said 30 spool and ratchet wheel, mechanism for resiliently forcing said spool and wheel toward each other, and means for adjusting the operation of said resilient mechanism.

17. In a device of the kind described, ribbon carrier mechanism comprising a collar rigidly held in position, and a shaft rotatably supported by said collar, in combination with a ribbon spool and a ratchet wheel mounted upon said shaft and adapted to 35 frictionally engage said collar between them, means for preventing rotation between said spool and ratchet wheel, and means for adjusting the frictional engagement between 40 said spool and ratchet wheel and said collar. 45

In testimony whereof, I have hereunto signed my name in the presence of two (2) subscribing witnesses.

DANIEL W. SHIEK.
